RAZOR BLADE HANDLE OR HOLDER

Nels S. Olesen, Sidney, Mont.

Application February 13, 1945, Serial No. 577,641

2 Claims. (Cl. 30—153)

1

The present invention relates to new and useful improvements in handles or holders for safety razor blades whereby to provide safe and effective gripping means for the blade while using the blade as a cutter.

An important object of the invention is to provide a handle for safety razor blades to provide a cutter adapted for use by dressmakers, model makers, carpenters, leather workers and the like.

It is also an important object of the invention to provide a sheath or guard for the blade when not in use together with means for pivotally attaching the sheath or guard to the handle for swinging the sheath into and out of position for enclosing the cutting edge of the blade.

Other objects and advantages reside in the details of construction and operation as more fully hereinafter described and claimed, reference being had to the accompanying drawing forming part hereof, in which:

Figure 1 is a side elevational view showing the sheath or guard with the blade positioned therein.

Figure 2 is a similar view showing the guard in its open position.

Figure 3 is an end elevational view, and

Figure 4 is a sectional view taken substantially on a line 4—4 of Figure 1.

Referring now to the drawing in detail wherein for the purpose of illustration I have disclosed a preferred embodiment of the invention, the numeral 5 designates the handle which is constructed of an elongated strip of metal bent upon itself and with the longitudinal edges of the material curved inwardly as indicated at 6 in substantially close abutting relation to provide a handle of tubular construction having a reinforcing strip of metal 7 positioned therein at its inner end.

The edges of the material adjacent the outer end of the handle are slightly spaced apart as indicated at 8 to provide a slot in the lower edge of the handle adapted to slidably receive a razor blade 9 of a type provided with a reinforced back edge 10 adapted for slidable insertion in the open outer end of the handle.

The lower edges of the handle 5 are provided with a pair of downwardly extending tongues 11 having a pin 12 inserted therethrough and on which is pivotally mounted a pair of guard plates 13 and 14 adjacent the inner upper edge of the latter.

The plates 13 and 14 are connected at their central portions by a rivet or the like 15 and the upper edges of the plates are bent in substantially

2

diverging relation with respect to each other and with their upper edges rolled as indicated at 16 for receiving the blade 9 between the plates 13 and 14 and with the upper edges of the plates also adapted for receiving the lower edge of the front end of the handle 5 in friction gripping relation therewith to retain the guard in a position for enclosing the blade.

The lower edges of the guard are likewise bent 10 in diverging relation with respect to each other so that when the guard is pivoted on the pin 12 to uncover the blade 9 the lower edge of the guard may then be swung upwardly for receiving the lower edge of the rear portion of the handle as 15 will be apparent from an inspection of Figure 2 of the drawing whereby to secure the guard in its open position.

The rear end of the handle 5 may be formed with an opening 17 by means of which the handle 20 may be suspended from a nail or other article when not in use.

From the foregoing it will be apparent that the handle 5 may be constructed of relatively light weight thin sheet metal and the handle will be 25 maintained in a rigid position by reason of the reinforcing strip 7 inserted in the hollow rear end of the handle.

In view of the foregoing description taken in conjunction with the accompanying drawings it 30 is believed that a clear understanding of the construction, operation and advantages of a tool of this character will be quite apparent to those skilled in the art. A more detailed description thereof is accordingly deemed unnecessary.

35 It is to be understood, however, that even though I have herein shown and described a preferred embodiment of my invention that the same is susceptible to certain changes fully comprehended by the spirit of the invention as herein 40 described, and the scope of the appended claims.

Having thus described the invention, what I claim is:

1. A safety razor blade holder comprising a substantially flat tubular handle having a longitudinally extending slot in its lower edge at the front end thereof and adapted for receiving one edge of a safety razor blade, a tongue extending downwardly from the lower edge of the handle rearwardly of the blade and a pair of plates secured to each other intermediate their edges and pivoted on said tongue adjacent one end of said plates, said plates diverging at their upper and lower edges and adapted for respectively receiving and frictionally engaging the lower edge of the handle when the blades are swung rearward-

ly and for frictionally engaging and enclosing the blades when the blades are swung forwardly.

2. A safety razor blade holder comprising a substantially flat tubular handle, an elongated rigid strip inserted in the rear end of the handle to reinforce the latter, said handle having a longitudinally extending slot in its lower edge at the front end thereof and adapted for receiving one edge of a safety razor blade for positioning in the front end of the handle, a tongue extending downwardly from the lower edge of the handle rearwardly

10

of the blade and a pair of plates secured to each other intermediate their edges and pivoted on said tongue adjacent one end of said plate, said plates having flared upper and lower edges adapted for respectively receiving and frictionally engaging the lower edge of the handle when the plates are swung forwardly and rearwardly on the handle, said plates forming a guard for the blade when moved into its forward position.

NELS S. OLESEN.
